ABSTRACT: A computer circuit for generating signals related to the ballistics of a plurality of projectile or ammunition types, the signals including time of flight, superelevation, and ballistics drift signals. The computer includes a plurality of parallel channels, and a first adjustable operational amplifier, which operates on the range information by a selected ballistics normalizing transfer function to generate an individual normalized range signal for a selected individual one of the plurality of projectile or ammunition types, a first multiplier means for multiplying the normalized range signal received from the operational amplifier by a partial derivative of non-standard air pressure and temperature, each parallel channel including a function generator coupled to receive and operate on the normalized range signal with a nonlinear transfer function common to the ballistics of all of the projectile types for generating an exponential function signal related to the selected projectiles, and a second adjustable operational amplifier coupled to the function generator for operating on the function signal by a selected individual unnormalizing transfer function for each projectile for generating signals related to the ballistics of the projectile, such as superelevation and time of flight on each channel and second and third multiplier means in each channel respectively coupled to multiply the superelevation signal and the time of flight signal by the partial derivative of nonstandard air temperature and air pressure conditions and by the partial derivative of nonstandard propellant grain temperature and effective full charge to correct for changes in standard conditions.

ELECTRONIC BALLISTIC COMPUTER FOR TANK FIRE CONTROL SYSTEM

BACKGROUND OF THE INVENTION

This invention relates generally to analog computers, and relates more particularly to a computer for generating signals which are related to functions of an input signal for standard conditions and the partial derivative of any variations in the standard conditions.

In computer circuits such as, for example, ballistic computers, range information has heretofore been fed to a computer circuit which would produce output signals related to the ballistics of a projectile when the physical characteristics such as its velocity, ambient atmospheric condition, gravitational conditions, the shape, the mass, and the spin were known or assumed. Generally, these signals were generated by function generators which were specifically mechanized for each specific projectile. For example, function generators have been mechanized using electromechanical range followup serves to position the armatures of padded range function potentiometers. Since other projectiles could have other ballistics characteristics as a result of different velocities, masses, shapes, and so forth, it became necessary to remechanize the function generator so that the generated output signals were related to the ballistics of the new projectile.

Heretofore the effects of variations in the variables from their standard values have been handled in one of three ways when the variations have been small relative to the absolute values. These ways have been to ignore the variations, to fully mechanize the circuit, disregarding the limited dynamic range of the variables, and to mechanize the circuit with a first order Taylor series approximation. For the general case of several variables such as $F(u, v, w)$ the mechanization equation for the Taylor series method would be $F(u_0, v_0, w_0) + F'(u, v_0, w_0)(u-u_0) + F'(v, u_0, w_0)(v-v_0) + F'(w, u_0, v_0)(w-w_0)$. In order to mechanize this equation it would be necessary to mechanize the function $F(u_0, v_0, w_0)$ for standard conditions, the partials $F'(u, v_0, w_0)$, $F'(v, u_0, w_0)$ and $F'(w, u_0, v_0)$, multiply each of the partials by the corresponding change in its variable and sum the four terms together. Thus, it was necessary to implement function generators for each partial and to sum the partials with the function. Also, the implication of the method is that there is no significant effect of a change in one variable on the effect due to a change in another.

SUMMARY OF THE INVENTION

Accordingly, it is an object of this invention to provide improvements in a computer which is operable to generate signals related to the function of input signals for standard conditions and variations in the standard conditions.

Another object of this invention is to provide a ballistic computer circuit which is operable to produce ballistics function signals related to the ballistics of a plurality of projectile types for standard conditions and for variations in the standard conditions.

Another object is to provide a ballistic computer in which selected ballistic signals are operated on as constants to correct for ballistic deflection angles and kinematic angles.

Still another object is to provide improvements in a ballistic computer having the advantages that: a small number of function generators can be utilized for producing functions of an input signal having one or more variables; variations in nonstandard conditions including air density as a result of atmospheric pressure and temperature variation, variations in the drag coefficient as a result of changes in the mach number due to changes in air temperature, changes in muzzle velocity as a result of tube wear and propellant temperature, and changes in crosswind and range wind coefficients as a result of any of the above can be compensated for outside of the function generator, and that lends itself to solid state implementation, is simplified relative to other known devices, and has a small size.

Other objectives of this invention can be attained with a computer circuit having one or more parallel channels wherein each channel is operable to receive input information, such as a range signal when the computer is implemented as a ballistics computer. The range signal R which is preferably an AC modulated signal $R \sin \omega t$ but can be DC and is also hereinafter referred to by its magnitude R for purposes of simplicity of symbols is first fed through an adjustable ballistics term multiplier which normalizes the range information R with a specific range normalizing transfer function or term R_n , derived from standard ballistic and environmental conditions for the selected projectile type. Thereafter, the normalized range information R/R_n is fed through a multiplier circuit which operably multiplies the signal by the partial derivative of nonstandard air temperature and pressure. The general case multiplication factor is a first order in-line partial approximation

$$\left(1 + K \frac{\Delta u}{u} \right)$$

of a partial derivative where for a common case if:
 $f(x) = u^k$

then

$$f'(x) = \frac{kf(u)}{u}$$

and

$$k = \frac{uf'(u)}{f(u)}$$

for the conditions:

$$\Delta u \ll u$$

when

$$k > 1$$

More specifically, for a ballistic computer the in-line partial derivative is for changes ΔR_n in the normalizing term $1/R_n$ as a result of variations in air pressure ΔP and air temperature ΔT . Consequently, the in-line partial multiplication correction factor becomes

$$\left(1 \pm \frac{\Delta R_n}{R_n} \right)$$

In other words, the function is multiplied by a term related to the ratio of the change in a condition to a standard condition to produce a product and is also summed with this product. Furthermore, since it has been determined that the normalizing term $1/R_n$ is inversely proportional to a function of air temperature T and proportional to air pressure P , the factor $\Delta R_n/R_n$ is proportional to

$$\frac{\Delta P}{P} - k \frac{\Delta T}{T}$$

Then the partially corrected signal is fed in parallel on each of the plurality of channels to a function generator which operates on the normalized range signal in accordance with a predetermined transfer function, which itself is normalized, and therefore is common to a multiplicity of projectile types. The output of each individual function generator is then fed to another individual adjustable ballistics term multiplier which operates on the received function signal with a specific unnormalizing transfer function to produce an output signal on each channel related to the selected projectile. The resulting output signals from these last-mentioned ballistics term multipliers include time of flight information t , and superelevation information ϵ_0 related to the ballistics of the selected projectile at the particular range. By adjusting the two multipliers, the ballistics terms are changed to those associated with another projectile type. Both the superelevation signal and the time of flight signal are fed through other multiplier circuits which multiply the signals by the partial derivative of nonstandard air temperature and pressure and through another multiplier circuit which further multiplies by a first order approximation

$$\left(1 + k \frac{\Delta V_o}{V_o}\right)$$

of a partial derivative of nonstandard propellant grain temperature and effective full charge whereupon the superelevation signal and the time of flight signal are corrected for non-standard conditions. More specifically, since the partial derivative is for initial velocity V_o , the partial derivative is for change in initial velocity ΔV_o due to changes in propellant grain temperature T_g and effective full charge EFC. Consequently, the in-line partial multiplication factor becomes

$$\left(1 - k \frac{\Delta V_o}{V_o}\right).$$

Furthermore, since superelevation is inversely proportional to a function of initial velocity V_o and time of flight is inversely proportional to initial velocity, the in-line partial multiplication factor for superelevation becomes

$$\left(1 - 2 \left[K \frac{\Delta T_g}{T_g} - f(EFC) \cdot k_e \right]\right)$$

and for time of flight becomes

$$\left(1 - \left[K \frac{\Delta T_g}{T_g} - f(EFC) \cdot k_e \right]\right).$$

For the more general case the in-line partial technique for multiplier function $F(u, v, w)$ would be implemented with a single function generator for producing the function $F(u_o, v_o, w_o)$ for predetermined conditions and multiplying this function by the in-line partial multiplication factors

$$\left(1 + k \frac{\Delta u_o}{u_o}\right), \left(1 + k \frac{\Delta v_o}{v_o}\right), \text{ and } \left(1 + k \frac{\Delta w_o}{w_o}\right).$$

Furthermore, the computer compensates for ballistic drift by multiplying the superelevation signal by a separate ballistic constant for each selected ammunition and compensates for crosswind effects by multiplying the time of flight signal by separate ballistic constants for each selected ammunition.

Other objects, features and advantages of this invention will become apparent upon reading the following detailed description and referring to the accompanying drawings wherein:

FIGS. 1A and 1B, taken together as indicated in FIG. 1C, are block diagrams illustrating the ballistic computer and resolver circuit;

FIG. 2 is a schematic diagram of an adjustable ballistic term multiplier of the type used in the computer illustrated in FIGS. 1A and 1B;

FIGS. 4A through 4F are timing diagrams of the waveforms of signals developed in the master slave multiplier of FIG. 3;

FIG. 5 is a schematic diagram of a function generator circuit of the type used in the computer circuit illustrated in FIG. 1A and includes a rectifier, a break point selector, and a straight line approximation function generator;

FIG. 6 is a diagram of one signal waveform produced by the function generator circuit of FIG. 5;

FIG. 7 is a circuit diagram of the follow and clamp circuit used in the computer circuit illustrated in FIG. 1B; and

FIG. 8 is an analog switch of the type used in the computer circuit of FIG. 1B.

DETAILED DESCRIPTION OF A PREFERRED EMBODIMENT

Referring now to an embodiment of the ballistics computer in more detail, reference is made to FIGS. 1A and 1B, wherein range information $R \sin \omega t$ and nonstandard condition information are fed into a computer which generates a superelevation signal ϵ , a time of flight signal t_f , a ballistic drift signal η_o , and a crosswind coefficient η_w , in accordance with ballistic equations whereupon these signals are used for generating fire control signals such as elevation E , and deflection D .

Once the range is known, the ballistic characteristics of the projectile and environmental conditions must be known in

order to generate fire control signals in accordance with the ballistic equations. For example, it is desirable to know the effects of ballistic conditions, such as the projectile's mass, initial velocity, and environmental conditions such as shape, size, spin velocity, the air density, air temperature, air pressure, crosswind, propellant temperature, angular turret rate, etc.

Since many of the ballistic characteristics will differ for different projectiles, or ammunitions, the resulting signals such as superelevation ϵ , time of flight t_f , ballistic drift η_o , and crosswind coefficient K_{cv} will also differ for each projectile.

It has been discovered that the nonlinear equations of ballistic flight from which standard condition superelevation ϵ_o , and standard condition time of flight t_{fo} are derived, can be produced for a plurality of projectiles by: a first variable multiplier 954 which multiplies or operates on the range signal R by an individual ballistic term including an individual normalizing transfer function $1/R_n$ to produce a normalized range signal R/R_n for each individual projectile; function generating circuits 956 and 958 in two parallel channels which operate on the normalized range signal with a single predetermined transfer function common to the ballistics of a plurality of projectile types for generating the nonlinear function signals $f_e(R/R_n)$ and $f_t(R/R_n)$, respectively, which are related to the selected projectiles; and variable multipliers 960 and 962 for multiplying or operating on the nonlinear function signals by individual second ballistic terms on unnormalizing transfer functions ϵ_{no} and t_{no} , which are related to the selected individual projectile. It should be stated that the ballistic terms R_{no} , ϵ_{no} and t_{no} can be considered constants or linear for a set of standard conditions.

For example, the approximated equation for standard conditions superelevation ϵ_o which is the angle by which the projector (such as a gun) is pointed above the line of sight to a target, is:

$$\epsilon_o = \frac{mg}{2KV_o^2} \left(\frac{e^{2RK/m} - 1}{2RK/m} - 1 \right) \quad (1)$$

and the approximated equation for standard conditions time of flight t_{fo} of the projectile is:

$$t_{fo} = \frac{m}{KV_o} (e^{RK/m} - 1) \quad (2)$$

where

K_D = drag coefficient

R = range

$K = pd^2 K_D$

p = air density

d = projectile diameter

m = projectile mass

V_o = projectile initial velocity

g = gravity

Ballistic drift η_o for standard conditions is proportional to superelevation ϵ_o according to the following equation:

$$\eta_o = \frac{-K_d \epsilon_o}{V_o} \quad (3a)$$

where K_d is a term, dependent upon projectile inertia, spin velocity, and lift and moment coefficients, which may be determined for each ammunition. The crosswind coefficient η_w for standard conditions is found by

$$\eta_w = V_w K_w t_f \quad (3b)$$

where K_w is an ammunition dependent coefficient.

As previously stated, it has been determined that signals which are a function of the ballistics equations can be produced by circuits which operate on the range information R in accordance with transfer conditions for ballistic terms and normalized functions.

For example, superelevation ϵ_o for standard conditions is produced by a circuit which operates on a range signal R in accordance with the following approximate equation:

$$\epsilon_n = \epsilon_{no} \left(\frac{e^{2(R/R_n)}}{2(R/R_n)} - 1 \right) = \epsilon_{no} f_n(R/R_n) \quad (4)$$

where the transfer functions:

$$\epsilon_{no} = \frac{mg}{2KV_o} = \frac{mg}{2pd^2V_oK_D} = \frac{R_n}{2V_o^2} \quad (5)$$

$$R_n = \frac{m}{K} = \frac{m}{pd^2K_D} \quad (6)$$

$$= \frac{KnmTg^2}{d^2Pa(Ta^{1/2} - K_t)} \quad (7)$$

where:

Ta = air temperature

Pa = air pressure

Kn = projectile ballistic constant

K_t = temperature coefficient.

A signal related to time of flight t_{no} for standard conditions is produced by a circuit which operates on a range signal R in accordance with the following approximate equation:

$$t_{no} = t_{no} (e^{R/R_{no}} - 1) = t_{no} f_t(R/R_n) \quad (7)$$

where the transfer function:

$$t_{no} = \frac{m}{KV_o} = \frac{m}{pd^2V_oK_D} \quad (8)$$

From these equations, it can be seen that, in implementing the circuits, transfer functions R_n , ϵ_n , and t_n are ballistic terms which are related to the particular projectile or ammunition's ballistic and environmental condition, and can be treated as linear for any fixed set of standard conditions, while transfer functions $f_n(R/R_n)$ and $f_t(R/R_n)$ are functions which are independent of the projectile type and condition or, in other words, which are common to all of the projectile types. The advantage of this is that only one such nonlinear function generator per ballistic signal need be mechanized for a plurality of projectile types and that nonstandard conditions signals can be applied to the computer outside of the function generator, as will be explained subsequently.

Referring to the block diagram of FIG. 1A in more detail, the range signal R is first normalized by multiplying by a standard condition normalizing term or individual transfer function related to a selected individual one of a plurality of ammunition types $1/R_{no}$ using a ballistics constant multiplier circuit 954, which is hereinafter also referred to as ballistic term multiplier, and which is adjustable for each ammunition.

The normalizing term $1/R_{no}$ is corrected for changes $1/\Delta R_n$ resulting from variations in air pressure ΔP and changes in air temperature ΔT by multiplying the term by an in-line partial multiplication factor $(1-B)$ where:

$$B = \Delta R_n / R_n$$

Consequently, the equations for superelevation ϵ_1 and time of flight t_1 partially corrected for nonstandard conditions become:

$$\epsilon_1 = \epsilon_0 (1 - B)$$

$$\epsilon_1 = \left(\frac{gR_n}{2V_o^2} \right) \left[\frac{e^{2(R/R_{no})} \left(1 - \frac{\Delta R_n}{R_n} \right) - 1}{2(R/R_n) \left(1 - \frac{\Delta R_n}{R_n} \right) - 1} \right]$$

$$t_1 = \frac{R_n}{V_o} \left(e^{R/R_{no}} \left(1 - \frac{\Delta R_n}{R_n} \right) - 1 \right)$$

As previously stated, the normalizing term $1/R_n$ is inversely proportional to a function of air temperature T and proportional to air pressure P whereupon the factor B can be produced by the portion of the in-line partial derivative circuit of FIG. 1A which includes as a portion thereof, a summing amplifier 940. The summing amplifier 940 receives the sensed air temperature input signal $\Delta T/T_o$ at one input and multiplies it by a temperature constant K . The summing amplifier 940 also receives the sensed air pressure input signal $\Delta P/P_o$ at a second input terminal. These signals are summed and the output signal B of the amplifier 940 then becomes:

$$B = \frac{\Delta R_n}{R_n}$$

$$= \frac{\Delta P}{P_o} - K \frac{\Delta T}{T_o}$$

As will be explained in more detail subsequently with reference to FIGS. 1A and 1B, the partially corrected superelevation signal ϵ_1 and the time of flight signal t_1 are fully corrected for nonstandard conditions by further multiplying them by the in-line partial multiplication factors $(1+B)$ and $(1-KH)$ which are respectively dependent upon variations in the normalizing term $1/R_n$ as a result of variations in air temperature ΔT and air pressure ΔP and dependent upon variations in initial velocity V_o as a result of variations in a function of effective full charge EFC and variation in propellant grain temperature ΔT_g .

The partially corrected superelevation signal ϵ_1 is thus further corrected for nonstandard conditions and is identified by the equation:

$$\epsilon = \epsilon_1 (1+B)(1-KH)$$

$$= \epsilon_1 (1 + \Delta R_n / R_n) (1 - 2(\Delta V_o / V_o))$$

$$\text{where } B = \Delta R_n / R_n \text{ and}$$

$$H = \Delta V_o / V_o$$

The partially corrected time of flight signal t_1 is further corrected for nonstandard conditions and becomes:

$$t = t_1 (1+B)(1-KH)$$

$$= t_1 (1 + \Delta R_n / R_n) (1 - (\Delta V_o / V_o))$$

The factor H can be produced by a second in-line partial derivative circuit of FIG. 1A wherein a sensed propellant grain temperature signal $\Delta T_g/T_g$ is received by an adjustable ballistic term multiplier 942, multiplied by a separate ballistic term K_g for each selected ammunition, and is then fed to one input of a summing amplifier 948. An effective full charge signal (EFC) is received by an adjustable ballistic term multiplier 944, is multiplied by a separate ballistic term K_e for each selected ammunition, and is fed through a function generator 946. The function generator 946 can be a 2 or more straight line approximation function generator of a type to be described in more detail subsequent for producing an output signal $f(K_e EFC)$ which is fed to another input of the summing amplifier 948. The resulting output signal of amplifier 948 is the factor H where:

$$H = \Delta V_o / V_o$$

$$= f(K_e EFC) - K(\Delta T_g / T_g)$$

A nonstandard temperature-pressure coefficient signal B , which is to be applied to the standard condition normalized range signal R/R_{no} is fed to and reproduced at the output of a master multiplier 964 which forms part of the first and second in-line partial derivative multiplier, in response to air temperature and pressure sensor inputs $\Delta T/T_o$ and $\Delta P/P_o$. The standard condition normalized range signal R/R_{no} , when applied to one input of a slave multiplier 966 in the first in-line partial derivative multiplier, is multiplied by the pressure-temperature coefficient B to produce an output signal $R/R_{no}(B)$ which is fed to an inverting input of an operational amplifier 968 which forms part of the first in-line partial derivative multiplier. The master-slave multiplier is of the general type described in U.S. Pat. No. 3,493,737, issued to Roger H. Edelson, on Feb. 3, 1970 and assigned to the same assignee. The signal R/R_{no} is also fed directly to a noninverting input of the operational amplifier 968 to produce an output signal:

$$R/R_{no}(1-B) = R/R_n$$

where

R/R_{no} is the normalized range signal for standard conditions; and

R/R_n is the normalized range signal for nonstandard pressure-temperature conditions; and

$$B = \left(\frac{\Delta P}{P_o} - K \frac{\Delta T}{T_o} \right)$$

where

ΔP is the change in air pressure from a standard condition pressure;

P_o is the standard condition air pressure;

K is a temperature coefficient;

ΔT is the change in air temperature from a standard condition air temperature; and

T_o is the standard condition air temperature.

The normalized range signal R/R_n is then fed to function

generators 956 and 958 which are connected in parallel circuit relationship to produce nonlinear ballistic function output signals $f_e(R/R_n)$ and $f_e(R/R_n)$, respectively in accordance with their single predetermined transfer functions. These nonlinear function output signals are then fed to ballistic constant multipliers 960 and 962 respectively, which are hereinafter also referred to as ballistic term multiplier, and which multiply them by the unnormalizing standard condition ballistic terms or transfer functions ϵ_{no} and ϵ_{no} , respectively for the selected projectile type. Consequently, the output signal $\epsilon_{no}f_e(R/R_n)$ of the ballistic constant multiplier 960 is related to the superelevation ϵ_1 for the particular projectile at the particular range R in accordance with the preceding ballistic equation (equation 4) which is partially corrected for nonstandard temperature-pressure conditions. The output signal $\epsilon_{no}f_e(R/R_n)$ of the ballistic constant multiplier 962 is related to the time of flight t_n of the selected projectile at the particular range R in accordance with the preceding equation for time of flight t_n (equation 7), which is partially corrected for nonstandard temperature-pressure conditions.

Referring to FIG. 1A, a master multiplier 970 which forms part of the third in-line partial derivative multiplier receives grain temperature and effective full charge sensor input signals $(\Delta T_g K_g/T_g - f(E.F.C.)_e)$ for producing the muzzle velocity coefficient H which, along with the temperature-pressure coefficient B is applied in series circuit with the function generators to correct the partially corrected superelevation ϵ_1 and time of flight t_n signals by means of the circuit illustrated in FIG. 1B. The partially corrected superelevation signal ϵ_1 is fed through a first slave multiplier 972 which forms part of an in-line partial derivative multiplier circuit and is multiplied by the temperature-pressure coefficient B to produce an output signal $\epsilon_1(B)$ which is fed to an input of an operational amplifier 974 which also forms part of this in-line partial derivative multiplier circuit. The partially corrected superelevation signal ϵ_1 is also fed directly to another input of the operational amplifier 974 which also forms part of this in-line partial derivative multiplier circuit, whereupon the output signal thereof on the channel becomes $\epsilon_1(1+B)$. This output signal is then fed through a second slave multiplier 976 which forms part of another in-line partial derivative multiplier circuit wherein it is multiplied by the muzzle velocity coefficient H to produce a signal $\epsilon_1(1+B)H$ which is fed to an input terminal of the operational amplifier 978 in this same in-line partial derivative multiplier circuit to invert and amplify the input signal by a factor -2 . The signal $\epsilon_1(1+B)$ is also fed directly to another input of the operational amplifier 978, whereupon the operational amplifier produces a superelevation output signal ϵ on the channel which is corrected for nonstandard conditions where:

$$\begin{aligned} \epsilon &= \epsilon_1(1+B)(1-2H) \\ H &= \Delta V_o/V_o \\ &= f(E.F.C.)_e (\Delta T_g/T_g) K_{ga} \end{aligned}$$

where:

$f(E.F.C.)_e$ is an empirically derived function of effective full charge for a selected ammunition A ;

ΔT_g = change in propellant grain temperatures from standard value;

T_g = standard condition propellant grain temperature;

K_{ga} = a temperature coefficient for a selected ammunition.

The partially corrected time of flight signal t_n is fed through a first slave multiplier 980 which forms part of a separate in-line partial derivative multiplier wherein it is multiplied by the temperature-pressure coefficient B received from the master multiplier 964 to produce an output signal t_nB which is fed to one input of an operational amplifier 982 which also forms part of the in-line partial derivative multiplier circuit. The partially corrected time of flight signal t_n is also fed directly to another input of the operational amplifier 982 wherein the further corrected time of flight output signal $t_n(1+B)$ is produced on the channel. This further corrected time of flight signal is fed through a second slave multiplier 984 which forms part of still another in-line partial derivative multiplier circuit wherein it is multiplied by the muzzle velocity coefficient H to produce a signal $t_n(1+B)H$ which is fed to an inverting input

of an operational amplifier 986 of this same in-line partial derivative multiplier circuit. The further corrected time of flight signal $t_n(1+B)$ is also fed directly to another input of the operational amplifier 986 which produces a fully corrected nonstandard condition time of flight output signal t_f on the channel where:

$$t_f = t_n(1+B)(1-H)$$

This time of flight signal t_f is fed to a master multiplier 988 for use as a time of flight multiplier signal T , as will be explained in more detail shortly.

The computer 950 also generates a parallax correction signal p to compensate for the offset distance at the turret between the line of sight and the gun line. The range signal R is fed to a function generator 990 and a rectifier 992. As will be explained in more detail subsequently, the output of the rectifier is fed to a break point selector 994 which determines the gain slope and offset of the function generator 990 for producing a parallax correction output signal p at the range R wherein:

$$\begin{aligned} p &= (D_p/R) - (D_p/R_c) \\ &= D_p(1/R - 1/R_c) \end{aligned}$$

D_p is the offset distance between the line of sight and the gun line;

R is the measured range;

R_c is a crossover range where line of sight crosses the gun line.

For parallax elevation corrections:

$$\begin{aligned} p_e &= (D_{pe}/R) - (D_{pe}/R_c) \\ &= D_{pe}(1/R - 1/R_c) \end{aligned}$$

where:

D_{pe} is a constant for each tank.

For parallax deflection correction:

$$\begin{aligned} p_d &= (D_{pd}/R) - (D_{pd}/R_c) \\ &= D_{pd}(1/R - 1/R_c) \end{aligned}$$

where:

D_{pd} is a constant for each tank.

Referring now to the ballistic computer in more detail, the range signal R is fed to the ballistic term multiplier 954, illus-

trated in FIG. 2 for producing a normalized range signal R/R_n in accordance with the normalizing transfer function $1/R_n$ for each selected one of a plurality of projectiles. More specifically, the ballistic term multiplier 954 is an operational amplifier having a plurality of n parallel selectable gain set input re-

sistance circuit branches which each include one of a plurality of junction FET transistors 996 through 996 n connected in series with one of a plurality of resistors 998 through 998 n respectively, the resistance circuit branches being connected to one input of an amplifier 1000. The subscript n represents

the circuit elements in the n th resistance circuit and is equal to a corresponding number of projectiles. In operation, only one of the junction FET transistors 996 through 996 n is turned on by a positive voltage signal $+V$ applied to its gate terminal through a resistor of resistors 1002 through 1002 n , respectively,

while all other ones of the FETS 996 through 996 n are turned off by a negative voltage $-V$ applied to the gate terminals thereof through the other ones of respective resistors 1002 through 1002 n .

Assume, then, that the projectile or ammunition selected has a linear ballistic term or normalizing transfer function $1/R_{no}$, which is set into the ballistic term multiplier 954 as a normalizing transfer function by the sum of the series resistances in the circuit branch between the source terminal and drain terminal of FET transistor 996 when it is turned on, and the resistor 998 connected between the FET transistor 996 and one input of the operational amplifier 1000. In operation, an ammunition selection switch 1004 through 1004 n is positioned so that a $+V$ voltage is applied through the resistor 1002 to the gate terminal of FET transistor 996 to turn it on while all other FET transistors will have a $-V$ voltage applied to their gate terminals by the switch, such as 996 n , and are turned off. The operational amplifier 1000 can be a $\mu A709$ High Performance Operational Amplifier, manufactured by

Fairchild Semiconductor Corporation and described and illustrated in their handbook, Fairchild Semiconductor Linear Integrated Circuits Applications Handbook, 1967.

The operational amplifier 1000 is compensated for a gain of unity and a feedback resistor 1006 is connected between the output terminal of the operational amplifier 1000 and one input terminal thereof so that the gain of the the ballistic term multiplier 954 is proportional to the ratio of the resistance of feedback resistor 1006 and the sum of the resistances between the source terminal and drain terminal of the turned on FET transistor 996 and resistor 998 and can be expressed by the term $1/R_{no}$. The received range signal R is multiplied by the ballistic term transfer function $1/R_{no}$, whereupon the output signal of the ballistic term multiplier 954 is a normalized range signal R/R_{no} for standard conditions for the selected ammunition.

Any gain resulting from the resistance circuits associated with turned off FET transistors can be disregarded since the resistance between the source and the drain terminal is very high relative to other circuit resistances. The zero offset of operational amplifier 1000 can be set by a center pickoff on a potentiometer 1008 wherein the pickoff voltage is substantially zero volts and is applied to one input terminal of the operational amplifier 1000 through a resistor network.

For other projectiles, the ballistic term or transfer function $1/R_{no}$ will be different since the resistance of resistors 998 through 998n is selected to fit the different ballistic terms for different projectiles. Thus, the selected normalized range output signal R/R_{no} is specifically related to the selected projectile. The output signal R/R_{no} is then fed to the ballistic function generator 956 and the ballistic function generator 958.

Before being fed to the function generators the normalized range signal R/R_{no} on the main channel is corrected in series circuit for nonstandard air temperature and air pressure conditions by an in-line partial derivative multiplier including a master-slave time division multiplier 964-966. The time-division multiplier can be an electronic multiplier of the type described in U.S. Pat. No. 3,493,737, issued to Roger H. Edelson on Feb. 3, 1970 and assigned to the same assignee. Additional description of the operation of this type of multiplier is contained in the book ELECTRONIC ANALOG AND HYBRID COMPUTERS, (McGraw-Hill 1964) pp. 268-281, especially FIGS. 7-15 on pg. 273. In this type of multiplier output is the average of a train of pulses in which the duty cycle is the ratio of two variables and the amplitude is controlled by another variable. For purposes of convenience so that repeated reference to these publications is not necessary such a master-slave time-division multiplier is illustrated in FIG. 3 and described briefly herein as including the master portion 964 and the slave portion 966. Even though only one slave 966 is illustrated in FIG. 3, one master can be used to drive a plurality of slave circuits as is illustrated in FIG. 1A.

The master-multiplier 964 illustrated in FIG. 3 is coupled to receive DC input reference signal e_d and $em = (\Delta P/P_0) - K(\Delta T/T_0)$ for providing two rectangular wave output signals B and $\bar{B}$ that are equal in magnitude and phase but opposite in polarity. The master-multiplier 964 includes a first master inverter 1010 that is coupled to receive the DC input signal e_d and performs an inversion operation thereon, and provides a signal $-e_d$ which is the inverse of the received signal. A second master inverter 1012 receives the inverted DC input signal $-e_d$ and performs an inversion operation thereon and provides an output signal e_d . Accordingly, the first master inverter 1010 and the second master inverter 1012 fed the opposite polarity output signals e_d and $-e_d$, respectively, to a first master switch 1014 and a second master switch 1016.

The first master inverter 1010 also operates to adjust the gain of the $-e_d$ signal applied to the first master switch 1014 and applied through the second master inverter 1012 to the second master switch 1016. If a system gain of one is desired, the first master inverter 1010 can be set to provide signals to the master switches 1014 and 1016 that have a unity gain in relation to the amplitude of the DC output signal e_d . The second master inverter 1012 always operates with a gain of one. With a unity system gain, the e_d input must be larger than the DC input $(\Delta P/P_0) - K(\Delta T/T_0)$ for proper circuit operation.

The first master switch 1014 and the second master switch 1016 are further coupled to receive opposite polarity gating

signals A and $\bar{A}$ from the output terminals 1018 and 1020 of a switch driver 1022 to allow alternating sequential operation of the respective switches.

A summing integrator 1024 is coupled to receive the output of the first master switch 1014 and the second master switch 1016 and to receive the $(\Delta P/P_0) - K(\Delta T/T_0)$ input signal for summing or integrating the currents produced by the $(\Delta P/P_0) - K(\Delta T/T_0)$ input signal and the $-e_d$ and e_d reference signals. A threshold detector 1026 is coupled to receive the output of the summing integrator 1024 and changes threshold levels between a (+) and a relatively (-) threshold level in response to the trigger output of a trigger circuit 1028. When a threshold level is exceeded by the output signal received from the summing integrator 1024 the switch driver 1022 generates an output pulse which is fed to switch the polarity of its opposite polarity gating signals A and $\bar{A}$ the terminals 1018 and 1020 at the constant repetition rate of the trigger circuit 1028. The output of the trigger circuit 1028 is applied to the threshold detector 1026 to cause the threshold detector to change output states upon receiving trigger signals from the trigger circuit 1028, thereby maintaining the repetition rate of the master portion gating signal outputs A and $\bar{A}$ equal to the repetition rate of the trigger circuit 1028 with an asymmetrical duty cycle pulse as will be explained in more detail with reference to FIG. 4. The gating signal outputs A and $\bar{A}$ at terminals 1018 and 1020 are in duty cycle form (ratio of on-time to the sum of on-time and off-time) off-time) and are alternately sequentially switched from

$$+ \left(\frac{\Delta P}{P_0} - K \frac{\Delta T}{T_0} \right) \text{ to } - \left(\frac{\Delta P}{P_0} - K \frac{\Delta T}{T_0} \right)$$

and back again.

The slave multiplier 966 includes a first slave inverter 1030, a second slave inverter 1032, a first slave switch 1034 and a second slave switch 1036 that operates as described previously for the master inverters 1010 and 1012 and the master switches 1014 and 1016, respectively, of the master portion 964. However, the input to inverter 1030 is an AC signal $R/R_{no} \sin(\omega t)$, having a period that is long with respect to the period of the output A and $\bar{A}$ of the master multiplier. First slave switch 1034 and second slave switch 1036 are coupled to terminals 1018 and 1020 of the master portion 964 via gate terminals 1038 and 1040, respectively, of the slave multiplier 966 to alternately sequentially cause the first slave switch 1034 and the second slave switch 1036 to change state in accordance with threshold level changes being detected by the threshold detector 1026. The outputs of the first slave switch 1034 and the second slave switch 1036 are coupled together and applied to a low pass averaging or ripple filter 1042 to produce a filtered output signal product that can be represented by the following relationship:

$$(R/R_{no} \sin(\omega t)) \left(\frac{\Delta P}{P_0} - K \frac{\Delta T}{T_0} \right)$$

The master portion 964 divides the quantity

$$\left(\frac{\Delta P}{P_0} - K \frac{\Delta T}{T_0} \right)$$

by the quantity e_d to provide a quotient equal to

$$\left(\frac{\Delta P}{P_0} - K \frac{\Delta T}{T_0} \right) / e_d$$

65 while the slave portion 966 multiplies that quotient by the quantity $R/R_{no} \sin(\omega t)$ to produce a product illustrated above.

The operation of the master-slave time-division multiplier of FIG. 3 can best be understood with reference to FIG. 4 wherein: the waveforms A and $\bar{A}$ illustrate the gating voltage outputs A and $\bar{A}$ of the switch driver 1022 at the terminals 1018 and 1020, respectively; waveforms C and D illustrate the output current waveforms of the first master switch 1014 and the second master switch 1016, respectively; waveform E illustrates the output voltage waveform of the summing integrator 1024; and waveform F illustrates the output voltage waveform of the threshold detector 1026. All of the

11

waveforms of FIG. 4 are correlated to the specific times of t_0 , t_1 , t_2 , t_3 and t_4 with the period T_1 equal to t_1-t_0 and the period T_2 equal to t_2-t_1 .

At time t_0 the gating signal B at terminal 1018 goes negative and gates the first master switch 1014 to the "off" or nonconducting state, and the gating signal A at terminal 1020 goes positive and gates the second master switch 1016 to the "on" or conducting state. For the T_1 period the first switch 1014 remains "off" and the second switch 1016 remains "on." During the T_1 period the summing integrator 1024 receives current resulting from the reference level e_d provided by the second master switch 1016, and by the resulting

$$\left(\frac{\Delta P}{P_0} - K \frac{\Delta T}{T_0} \right)$$

current (not shown), and produces the negative-going ramp voltage E. Because master switch 1014 is nonconducting, there is no $-e_d$ charging current from the first master switch 1014 applied to the summing integrator 1024 during the T_1 period. When the negative-going ramp voltage output of the summing integrator 1024 of FIG. 3 reaches a negative (-) threshold level of the threshold detector 1026 controlled by the trigger circuit 1028 at time t_1 , the output signal F of the threshold detector 1026 changes from a negative output value to a positive output value. When the output of the threshold detector 1026 fed to switch driver 1022 goes from a negative value to a positive value the output of the switch driver 1022 changes the polarity of its gating signals A and $\bar{A}$ at terminals 1018 and 1020.

Therefore, at time t_1 , the gating signal A at terminal 1018 goes positive and the first switch 1014 changes from the "off" or nonconductive state to the "on" or conducting state, and the gating signal $\bar{A}$ at terminal 1020 goes negative and causes the second master switch 1016 to change from the "on" or conducting state to the "off" or nonconducting state. During the T_2 period, between times t_1 and t_2 , the first master switch 1014 remains "on" and the second master switch 1016 remains "off." Furthermore, during the T_2 period the summing integrator 1024 is charged from the negative (-) threshold level toward the positive (+) threshold level by the sum of the $-e_d$ current C from the first master switch 1014 (FIG. 3) and by the

$$\left(\frac{\Delta P}{P_0} - K \frac{\Delta T}{T_0} \right)$$

current, and produces the positive-going ramp voltage E. Because master switch 1016 is off there is no e_d charging current output from the second switch 1016 during the T_2 period. When the positive-going ramp voltage E applied to switch driver 1022 reaches the positive (+) threshold level at the threshold detector 1026 at time t_2 , as controlled by the output of trigger circuit 1028 the output F of the threshold detector 1026 changes from a positive output value to a negative output value. When the output F of the threshold detector 1026 goes from a positive value to a negative value, the output of the switch driver 1022 changes the polarity of its gating signals A and $\bar{A}$ at terminals 1018 and 1020. From time t_2 on in time the operation of the circuit of FIG. 3 repeats, since the time interval t_3-t_2 is identical with T_1 and the time interval t_4-t_3 is identical with T_2 .

Upon further analysis of the waveforms of FIG. 4, the master portion 964, or time-division portion of the time-division multiplier of FIG. 3, carries its division information (e_m/e_d) in the form of a duty cycle. The duty cycle is the ratio of the total "on" time (T_2-T_1) to total time (T_1+T_2). It should be recalled that there are three charging currents being applied to the summing integrator 1024 during this "total cycle time" (T_1+T_2). The

$$\left(\frac{\Delta P}{P_0} - K \frac{\Delta T}{T_0} \right)$$

current is applied during the (T_1+T_2) periods, while the e_d current D from the switch 1016 is only applied during the T_1 period and the $-e_d$ current C from the switch 1014 is only applied during the T_2 period. The average value of the charging

12

currents applied to the summing integrator 1024 is therefore given by the equation:

$$\left(\frac{\Delta P}{P_0} - K \frac{\Delta T}{T_0} \right) \left(T_2 + T_1 \right) + \frac{e_d}{R_2} (T_1) + \frac{(-e_d)(T_2)}{R_3} = 0$$

with R_1 , R_2 , and R_3 being various circuit resistances (not shown) which help control the system gain. For example, the summing integrator 1024 may contain an operational amplifier (not shown) in which R_1 , R_2 and R_3 are the input resistances, each being responsive to its respective one of the input signals

$$\left(\frac{\Delta P}{P_0} - K \frac{\Delta T}{T_0} \right)$$

15 e_d and $-e_d$ and connected to a common summing point. When the master portion 964 and its components are designed for a system gain of one, $R_1=R_2=R_3$ and the equation then becomes

$$\left(\frac{\Delta P}{P_0} - K \frac{\Delta T}{T_0} \right) (T_2 + T_1) + e_d (T_1) + (-e_d) (T_2) = 0$$

Dividing all the terms of the equation by $e_d (T_2+T_1)$ combining like terms, and transposing terms, the resulting expression then becomes:

$$\left(\frac{\Delta P}{P_0} - K \frac{\Delta T}{T_0} \right) = \frac{T_2 - T_1}{T_2 + T_1}$$

25 It has therefore been shown that the quotient

$$\left(\frac{\Delta P}{P_0} - K \frac{\Delta T}{T_0} \right)$$

30 is obtained by pulse width modulation and is contained in the duty cycle form of

$$\frac{T_2 - T_1}{T_2 + T_1}$$

35 The multiplication by the time-division multiplier is accomplished by the slave portion 966 by selectively applying the grating pulses A and $\bar{A}$ at the derived duty cycle and the negation thereof to the first slave switch 1034 and the second slave switch 1036 via the terminals 1038 and 1040, while applying the $-R/R_{no} \sin(\omega t)$ signal from inverter 1030 to switch 1034 and the $(R/R_{no}) \sin(\omega t)$ signal from inverter 1032 to switch 1036.

Since the switch 1036 is "on" or in the conducting state during T_2 of the total time (T_1+T_2) and "off" or in the nonconducting state during T_1 as controlled by waveform A, $(R/R_{no}) \sin(\omega t)$ current only flows through the switch 1036 to the averaging filter 1042 during the T_2 period. Averaging filter 1042 can be fabricated in accordance with the principles described in ELECTRONIC ANALOG AND HYBRID COMPUTERS, pp. 277-281. Also, since the switch 1034 is "on" or in the conducting state during the T_1 of the total time (T_1+T_2) and "off" or in the nonconducting state during T_2 as controlled by waveform $\bar{A}$, $(-R/R_{no}) \sin(\omega t)$ signal only flows through the switch 1034 to the averaging filter 1042 during the T_1 period. If the slave portion 966 is operated having a gain of one and the output signal of averaging filter 1042 is represented by $(R/R_{no}) \sin(\omega t)B$, then the flow of $(R/R_{no}) \sin(\omega t)$ and $(-R/R_{no}) \sin(\omega t)$ signal can be represented by the equation

$$e_o = \left[(R/R_{no}) \sin(\omega t) \frac{T_2}{T_2 + T_1} + (-R/R_{no}) \sin(\omega t) \frac{T_1}{T_2 + T_1} \right]$$

40 Factoring out the quantity $R/R_{no} \sin(\omega t)$ from the right-hand terms and combining terms, the equation becomes

$$R/R_{no} \sin(\omega t) B = R/R_{no} \sin(\omega t) \left[\frac{(T_2 - T_1)}{(T_2 + T_1)} \right]$$

45 with the substitution of

$$\frac{T_2 - T_1}{T_2 + T_1}$$

50 by its equality of

$$\frac{\Delta P}{P_o} - K \frac{\Delta T}{T_o}$$

$$e_d$$

the resulting equation becomes

$$(R/R_{no}) \sin(\omega t) B = \frac{e_s e_m}{e_d}$$

$$(R/R_{no}) \sin(\omega t) \left(\frac{\Delta P}{P_o} - K \frac{\Delta T}{T_o} \right)$$

$$e_d$$

It is noted that in the above equations the value of e_s represents the value of the AC normalized range signal $(R/R_{no}) \sin(\omega t)$ for the duration of a particular duty cycle; and as noted above the duration of the duty cycle is much shorter than the AC period of the signal $(R/R_{no}) \sin(\omega t)$, and hence the change in magnitude of $R/R_{no} \sin(\omega t)$ during any duty cycle is relatively small. This output signal $(R/R_{no}) \sin(\omega t) B$ is fed to the operational amplifier 968 of FIG. 1A. The partially corrected normalized range signal $R/R_n = R/R_{no} \sin(\omega t) (1 + \chi B)$ previously derived is the output of operational amplifier 968 and is fed to the function generators 956 and 958.

FIG. 5 illustrates a function generator 956 for producing an output function $f_c(R)$ via a plurality of line slope segments. The circuit includes a break point selector 1044 and a switched resistor network 1046, including a plurality of resistance branches which are selectively summed in response to output signals received from the break point selector 1044 wherein the selectively summed resistances are coupled to the input of an operational amplifier 1048 to vary its gain approximately in accordance with a single nonlinear exponential transfer function, such as the $f_c(R/R_n)$ function shown in FIG. 6.

The circuitry of FIG. 5 can be used with either a DC or an AC input analog voltage such as the normalized range signal (R/R_n) or $(R/R_n) \sin(\omega t)$. With an AC input signal a four-pole, two-position switch 1050 is placed in the AC position (reverse of that shown), so that both the range input signal $(R/R_n) \sin(\omega t)$ and an AC reference signal at the same frequency and phase as the range input signal $(R/R_n) \sin(\omega t)$; being applied to input terminals 1052 and 1054, respectively, can be converted into output DC voltages which are respectively proportional to the rms value of the respective AC voltages, by the use of precision rectifiers 1056 and 1058. Precision rectifier 1056 produces a +DC output voltage proportional to normalized range R/R_n , while precision rectifier 1058 produces a -DC output voltage proportional to the AC reference signal input. Normalized range signal $R/R_n \sin(\omega t)$ and the AC reference voltages are directly applied to the switched resistor network 1046 since they can be utilized therein without being converted into DC voltages first.

With a DC input analog voltage and a DC constant reference voltage, switch 1050 is placed in the DC position, as shown in FIG. 5. The DC normalized range signal R/R_n is then directly applied to both the break point selector 1044 and the switched resistor network 1046 via input terminal 1060. The DC constant reference voltage is applied via input terminal 1062 directly to the switched resistor network 1046, and also applied through inverter 1064 to the break point selector 1044, since a negative (-) DC reference voltage is required for proper operation of the break point selector 1044.

The circuitry of FIG. 5 will hereinafter be described for use with a DC normalized range signal R/R_n and a DC reference voltage. In the light of the foregoing and subsequent explanation it should be apparent how the function generator would operate with an AC normalized range signal $(R/R_n) \sin(\omega t)$ and an AC reference signal which would perform the same general function as the related AC signal to be described.

The break point selector 1044 includes a plurality of operational amplifiers 1066, 1068 and 1070. Each operational amplifier has an inverting input terminal designated by the number 2, a noninverting input terminal designated by the number 3, and an output terminal designated by the number 6. A resistor 1072 is connected between the noninverting input and ground in order to minimize the bias current error inherent in operational amplifiers. Comparison circuits composed of resistors 1074 and 1076, 1078 and 1080, and 1082 and 1084 are respectively parallel coupled through switch

- 1050 between input terminal 1060 and the output terminal of inverter 1064 for respective reception and comparison of the normalized range signal R/R_n and the DC constant reference voltage. The respective junctions of the pairs of resistors contained in each comparison circuit are respectively coupled to the inverting inputs of operational amplifiers 1066, 1068 and 1070. Each of operational amplifiers 1066, 1068 and 1070 produces a negative output signal when a positive voltage is coupled to its inverting input. With a distant target, the range 10 and hence the amplitude of the normalized range signal R/R_n is greater than with a close target. The size of the resistances 1074, 1076, 1078, 1080, 1082 and 1084 are chosen such that if the range progressively increases R operational amplifier 1066 is turned on first; then with a further increase in range R operational amplifier 1068 is turned on next; and with a still further increase in range R operational amplifier 1070 is turned on last. These turn on points for the operational amplifiers are reached when the normalized range signal R/R_n reaches voltage V_A , voltage V_B , and voltage V_C , as indicated by points a , b , and c in FIG. 6. When the voltage level V_A is exceeded by the input normalized range signal R/R_n , the output of operational amplifier 1066, which can be a Fairchild μ A709 high performance operational amplifier, manufactured by Fairchild Semiconductor Corporation and described and illustrated in their handbook, Fairchild Semiconductor Linear Integrated Circuits, Application Handbook, 1967, goes low or negative. The output of operational amplifier 1066 is fed through resistor 1084 to the base terminal of a PNP transistor 1086 to turn on the transistor and cause the voltage drop across the collector resistor 1088 to change from a negative to a positive voltage. The signal taken off the collector of transistor 1086 will hereinafter be referred to as switching or break point select signal A and will be positive in potential at this time. 20
- When the normalized range signal R/R_n exceeds the voltage level V_B , due to a further increase in the target range R , the output of operational amplifier 1068 goes low or negative. The output of operational amplifier 1068 is fed through resistor 1090 to the base terminal of a PNP transistor 1092 to turn on the transistor 1092 and cause the voltage drop across its collector resistor 1094 to change from a negative to a positive voltage. The signal taken off the collector of transistor 1092 will hereinafter be referred to as switching or break point select signal b and will be positive in potential at this time. 25
- If the target range should further increase, the amplitude of normalized range signal R/R_n will also increase. When the normalized range signal R/R_n exceeds the voltage level V_C , as indicated by point c in FIG. 6, the output of operational amplifier 1070 goes low or negative. The output of operational amplifier 1070 is fed through resistor 1096 to the base terminal of transistor 1098 to turn on the transistor 1098. Upon the conduction of transistor 1098 the voltage drop across the collector resistor 1100 changes from a negative to a positive voltage. The signal taken off the collector of transistor 1098 will hereinafter be referred to as switching or break point select signal c and will be positive in potential at this time. 30
- These switching or break point select signals a , b , and c are fed to the resistor network 1046 to selectively vary the gain of the operational amplifier 1048. 35
- The resistor network 1046 includes a first set of parallel resistance branches 1102 which are coupled to receive the normalized range signal R/R_n and are responsive to the application of the break point select signals a , b and c for setting the gain slope, or a , slope factor of the a_{μ} term, of the nonlinear function $f_c(R/R_n)$ produced at the output of operational amplifier 1048. The R/R_n factor of the a_{μ} term is the input 40 analog voltage R/R_n which is applied through switch 1050 to resistor 1104 and to the source terminals of FET transistors 1106, 1108 and 1110. This input analog voltage R/R_n , or R/R_n factor, in cooperation with the resistance presented to the inverting terminal of the operational amplifier 1048 by the first set of parallel resistance branches 1102, effectively results (through previously described circuit operation) in the 45 production of the a_{μ} term of the function $f_c(R/R_n)$ as

produced at the output of operational amplifier 1048. The resistor network 1046 also includes a second set of parallel resistance branches 1112 which are connected in common to input terminal 1062 through switch 1050 for reception of the reference voltage, and are responsive to the application of the reference voltage and the break point selector signals a , b and c to bias the projected gain slope level to intercept the coordinates of the function $f_e(R/Rn)$ at the points a , b and c of FIG. 6 which respectively represent the voltages V_A , V_B and V_C . These coordinate intercepts determine the ordinate intercept points, or voltages, b_1 , b_2 , b_3 , and b_4 . The intercept voltage b_1 occurred before the break point select voltage V_A , since it is part of the a_1x+b_1 equation of the first line segment. The production of the b_1 term (representing the intercept voltages b_1 , b_2 , b_3 and b_4) of the nonlinear function $f_e(R/Rn)$ at the output of operational amplifier 1048 is achieved by the circuit operation of the resistance presented to the inverting terminal of the operational amplifier 1048 by the second set of parallel resistance branches in cooperation with the reference voltages.

More specifically, when the amplitude of the input analog range voltage is less than that of break point voltage V_A , only the slope set resistor 1104 and an intercept set resistor 1114 are connected to the input of operational amplifier 1048, since no positive point select signals a , b or c are received to turn on the junction FET transistors contained in the first set of parallel resistance branches 1102 and the second set of parallel resistance branches 1112. Therefore, the output of the operational amplifier 1048 will be described by the equation $f_e(R/Rn)=a_1x+b_1$ of the first line slope segment.

The operational amplifier 1048 includes an amplifier 1116 such as previously referenced μ A709 and has a feedback resistor 1118 connected between its output terminal (6) and its inverting input terminal (2). In addition, the noninverting input terminal (3) is connected through resistor 1120 to the reference potential to minimize the bias current error inherent in operation amplifiers. The combination of the slope set resistor 1104 and the intercept set resistor 1114 operate as gain set resistances wherein the gain of the operational amplifier is proportional to the ratio of the resistance of the feedback resistor 1118 and the sum of the parallel resistances of the slope set resistor 1104 (operating on the input signal (R/Rn)) and the intercept set resistor 1114 (operating on the reference voltage).

Under these conditions the function generator 956 will generate the first line segment illustrated in FIG. 6 until the increasing input analog voltage exceeds the voltage V_A (represented by point a in FIG. 6). When the amplitude of the input normalized range signal R/Rn exceeds the first break point or switching voltage V_A , the positive switching, or break point select, signal a is produced by the break point selector circuit 1044 and is fed through resistors 1122 and 1124 to the gate terminals of FET transistors 1126 and 1128 in the first set of parallel resistors 1102 and the second set of parallel resistors 1112, respectively, to turn them on. The sum of the parallel resistances of resistor 1122 and the resistance branch, including the resistance between the source terminal and the drain terminal of turned on FET transistor 1126 and resistor 1130 will effectively reduce the gain slope resistance of the operational amplifier 1048, thereby effectively increasing the slope of the second line slope segment between the voltage levels V_A and V_B , designated as points a and b in FIG. 6. In addition, for the intercept set bias, the sum of the parallel resistances of resistor 1114 and the resistance branch including the resistance between the source terminal and the drain terminal of turned on FET transistor 1128 and resistor 1132 operate on the reference voltage to bias the operational amplifier 1048 gain, so that a projection of the second line slope segment will intercept the ordinate of the graph in FIG. 6 at a predetermined point b_2 .

Similarly, third line slope segment between break point voltages V_B and V_C , as represented by points b and c in FIG. 6, is produced when the break point select signal b changes from a negative potential to a positive potential and is applied through resistor 1134 to the base electrode of FET transistor

1136 and through resistor 1138 to the base electrode of FET transistor 1140, respectively. The positive switching or break point select signal b turns on FET transistors 1136 and 1140 so that their respective source to drain resistances and the resistance of resistors 1142 and 1144, respectively, are summed in parallel with the previously described resistance branches to respectively further reduce the gain slope resistance of the operational amplifier 1048, thereby effectively increasing the slope of third line slope segment between voltage level V_B and V_C (designated as points b and c in FIG. 6) and, in cooperation with the reference voltage, to further bias the operational amplifier 1048 gain so that a projection of the third line slope segment will intercept the ordinate of the graph in FIG. 6 at a predetermined point b_3 .

The fourth line slope segment following the break point voltage V_C , as represented by point c in FIG. 6, is produced when the switching or break point select signal c changes from a negative voltage to a positive voltage and is applied through resistors 1146 and 1148 to the gate terminals of FET transistors 1150 and 1152, respectively, to turn them on. The resistance branch, including the resistance between the source terminal and the drain terminal of FET transistors 1150 and 1152 and the respective resistors 1154 and 1156 are respectively added in parallel to the previously described resistances to further increase the gain slope of the operational amplifier 1048 and to further bias the operational amplifier so that the fourth line slope segment, as so projected, would intercept the Y coordinate at a new intercept point b_4 .

It should be emphasized that although a function generator which is capable of generating four line segments has been described, it is possible to increase the accuracy of the curve approximation of this function generator by adding additional comparison circuits, operational amplifier circuits and transistor circuits to the break point selector 1044, and additional resistance branches in each of the first and second sets of parallel resistance branches 1102 and 1112 including FET transistors and the resistors, for each additional line segment desired. The generation of additional line segments at additional break points would more closely approximate the desired smooth curve for which the function is required. The resulting output signal $f_e(R/Rn)$ on the output terminal of operational amplifier 1048 is approximately the function previously described in the equations.

The resulting output signal $f_e(R/Rn)$ on the output terminal of operational amplifier 1048 is received by the adjustable ballistic term multiplier 960 (FIG. 1A) wherein it is multiplied by the linear unnormalizing ballistics transfer function ϵ_{no} . Structurally, the adjustable ballistics constant multiplier 960 is arranged the same as the adjustable ballistics term multiplier 954 illustrated in FIG. 2 with the exception that the value of the resistances 998-998n and feedback resistor 1006 are selected in accordance with the unnormalizing transfer function ϵ_{no} for each ammunition type. The output signal from this adjustable ballistics constant multiplier 960 is proportional to superelevation ϵ_1 in accordance with the previously described superelevation equations.

The ballistics function generator 958 for generating the nonlinear ballistic function $f_t(R/Rn)$ and the adjustable ballistic term multiplier 962 for multiplying the nonlinear function signal by the unnormalizing ballistic term or linear unnormalizing transfer function t_{no} illustrated in FIG. 1A are embodied in the same way as the ballistic function generator 956 of FIG. 5 and the adjustable ballistic term multiplier 954 of FIG. 2, respectively, with the exception that the resistances of the resistors therein are selected so that the resultant ballistic function signal output t_f will closely approximate the smooth curve and expression represented by time of flight equations for generating the partially corrected time of flight signal t_{f1} .

As previously described with reference to FIG. 1B the partially corrected superelevation signal ϵ_1 and the partially corrected time of flight signal t_{f1} are each fed through a pair of slave multipliers to further correct for nonstandard conditions in accordance with the partial derivatives B and H. More

specifically, the partially corrected superelevation signal ϵ_1 is fed through the slave multiplier 972, the operational amplifier 974, the slave multiplier 976 and the operational amplifier 978 to produce the superelevation output signals ϵ for non-standard conditions:

$$\epsilon = \epsilon_1(1+B)(1-H)$$

where

$$B = \Delta Rn/Rn$$

$$H = \Delta Vo/Vo$$

The partially corrected time of flight signal t_f is fed through the slave multiplier 980, the operational amplifier 982, the slave multiplier 984 and the operational amplifier 986 to produce the time of flight output signal t_f for nonstandard conditions:

$$t_f = t_f(1+B)(1-H)$$

where

$$B = \Delta Rn/Rn$$

$$H = \Delta Vo/Vo$$

These four slave multipliers 972, 976, 980 and 984 are all implemented the same way as the slave multiplier 966 as illustrated in FIG. 3. The master multiplier 970 for driving the slave multipliers 976 and 984 is implemented in the same manner as master multiplier 964 illustrated in FIG. 3.

The parallax correction signal p is produced by the function generator 990, rectifier 992 and break point selector 994 which are implemented in the same manner as the circuits of FIG. 5. Since, however, the function of parallax

$$p = D_p \left(\frac{1}{R} - \frac{1}{R_c} \right)$$

is inversely proportional to range it is generated as the function generator decreases the number of parallel resistance branches as the range increases, which is just opposite of the mode of operation described with reference to FIG. 5.

Referring back to the circuit of FIG. 1B, the elevation control signals E and deflection control signals D for driving the fire control system in elevation and deflection, respectively, are generated in response to the superelevation signal ϵ and time of flight signal t_f which have been corrected for ballistic drift angle η_d , wind deflection angle η_w , angular turret rate η_k , parallax p , jump D_j , E, and droop $Ed-Dd$.

The superelevation signal ϵ is fed through a ballistic term multiplier 1160 of the type illustrated in FIG. 2 wherein it is multiplied by a selected ballistic drift constant K_d for each selected ammunition and can include an in-line partial multiplier of the previous type to generate a drift angle signal η_d in accordance with the previously described equation. This drift angle signal η_d is then fed to one summing input of an operational amplifier 1162 whereafter the circuit will utilize this ballistic drift angle signal to correct the elevation control signal E and the deflection control signal D as will be explained in more detail shortly.

The crosswind signal V_w received from a wind sensor is fed through a variable ballistic term multiplier 1164 of the previously described type wherein it is multiplied by a crosswind coefficient K_w for each selected ammunition to generate the signal $V_w K_w$. This signal is then fed through a slave multiplier 1166 of the type illustrated in FIG. 3 wherein it is multiplied by the temperature-pressure correction coefficient B to generate an output signal $V_w K_w B$ which is fed to an inverting input of a summing operational amplifier 1168. The signal $V_w K_w$ is also fed directly to a noninverting input of the operational amplifier 1168 wherein the output signal $V_w K_w(1-B)$ is produced to correct for nonstandard conditions. This signal is fed through a slave multiplier 1170 wherein it is multiplied by the time of flight signal T ($T=t_f$) when a right lead lock and input signal R/LL from a hand control of the operator is on to produce the wind deflection angle signal η_w which is fed to a second input of the summing operational amplifier 1162 whereafter it is used to correct the deflection signal D and the elevation signal E.

The time of flight multiplication factor T for the slave multiplier 1170 is produced when the time of flight signal t_f is fed

to the master multiplier 988. The master-slave time-division multiplier 988-1170 are of the type illustrated in FIG. 3 and described above and can be operated with an AC input signal $e_m = t_f \sin \omega t$ received by the master multiplier 988 and a DC input signal $V_w K_w$ received by the slave portions 1170. As previously stated, the period of the AC signal $t_f \sin \omega t$ must be many times longer than the duration of the duty cycle of the master multiplier 988. As a result, the master portion will operate substantially as described above for a DC input signal for any particular duty cycle.

However, when the input signal $t_f \sin \omega t$ is an AC signal, the output

$$\frac{t_f \sin \omega t}{e_d} = \frac{T_2 - T_1}{T_2 + T_1}$$

of the master portion 988 will change from duty cycle to duty cycle giving a pulse width modulated output signal. For example for an input of $e_m = t_f \sin 0^\circ$, no e_m current will be applied

20 to the summing integrator 1024 and the output signal will be a rectangular wave where $T_1 = T_2$. As the $t_f \sin \omega t$ signal increases from $\sin 0^\circ$ to $\sin 90^\circ$, the time T_2 increases until the duration of T_1 is very short with respect to time T_2 . When the $t_f \sin \omega t$ signal changes through its period from $\sin 90^\circ$ to $\sin 270^\circ$, the duration of T_1 will increase until T_2 is short with respect to T_1 .

25 As the $t_f \sin \omega t$ signal changes from $\sin 270^\circ$ to $\sin 360^\circ$, the duration T_2 will increase and the duration of T_1 will decrease until a square wave output signal in which $T_1 = T_2$ results. The output of the master portion 988 will change as

30 described above for each cycle of e_m .

The first slave switch 1034 and the second slave switch 1036 receive the output T of the master portion 988 as described above and provide an output signal at their common outputs corresponding to the pulse width modulated output of

35 the master portion 988. The output of the first slave switch 1034 and the second slave switch 1036 are applied to an averaging filter 1042 to produce a filtered output signal that can be represented by the following relationship:

$$\frac{V_w K_w (1-B) t_f \sin \omega t}{e_d}$$

The waveforms A through F illustrated in FIG. 4 are applicable to the master-slave time-division multiplier for an AC signal $t_f \sin \omega t$ applied to the master portion 988 and a DC signal $V_w K_w(1-B)$ applied to the slave portion 1170.

45 The angular rate in azimuth ω_1 of the turret is fed through a follow and clamp circuit 1172 wherein it is stored as a DC signal when the right lead lock input signal R/LL is received.

50 A typical follow and clamp circuit operable to sample ω_e or ω_1 (FIG. 1B) in a disturbed or nondisturbed fire control system is illustrated in FIG. 7 and includes a switch 1182 responsive to a DC signal ω_1 . An amplifier 1184 has an input coupled to ground through a suitable resistor 1186 and coupled through a resistor 1188 to the switch 1182. Also, the output of the amplifier 1184 is coupled through a series connected feedback resistor 1190 and switch 1192 to the input thereof as well as being coupled through a parallel capacitor 1194 to the output of the amplifier. The switches 1188 and 1192 are respectively responsive to switch control units 1198

55 which is responsive to the right lead lock control signal R/LL . The switches 1188 and 1192 are closed for filter operation and are opened for hold operation when the R/LL is terminated, this condition being for disturbed and nondisturbed operation. For director operation, the switches 1188 and 1192 remain closed as shown so that filter action is provided. For all mechanizations, switch 1198 is closed in the absence of an R/LL signal. When utilizing the sample and hold circuit

60 release of the R/LL , switch 1198 causes the switches 1182 and 1192 to open so that the operator selected angular target tracking rate is stored as a DC signal ω_1 .

65 This DC signal is then fed through a slave multiplier 1174 of the type previously described wherein it is multiplied by the time of flight signal T to generate a kinematic lead angle signal $\omega_1 T$. If it is a one gyro system, this kinematic lead angle signal

70 75

$\omega_1 T$ is fed through an analog switch 1176a as a single gyro kinematic lead angle signal 72_k to another input of the operational amplifier 1162 for correcting the deflection signal D and elevation signal E.

The analog switches 1176a and 1176b illustrated in FIG. 8 receive the single gyro kinematic lead angle signal $\eta_k = \omega_1 t_f$ at one input terminal 1204 and the optional second gyro kinematic lead angle signal ω_{etf} , as will be explained in more detail subsequently, at a second input terminal 1206. The other two input terminals 1208 and 1210 are connected to a ground terminal. A switch signal R/LL is received at an input terminal 1212. This switch signal R/LL is normally at a low level when the computer is not in a COMPUTE mode, so that the inputs at terminals 1208 and 1210, which are at ground level, are coupled to the output terminal 1214 and 1216, respectively.

More specifically, when the switch signal R/LL applied to terminal 1212 is low, the interface diode circuit 1218 is forward biased so that one end of the base current resistor 1220 is at the ground level. This ground level signal is fed through the threshold circuit 1222, including two series diodes to reverse bias an NPN transistor 1224 off. In addition, a base emitter resistor 1226 is connected between the base terminal of the transistor 1224 and its emitter terminal. A biasing network including resistors 1228 and 1230 connected between the emitter terminal and a +12 v. terminal and a resistor 1232 are connected between the +12 v. terminal and the +50 v. level terminals at one end and the base terminal of transistor 1234 to maintain the base terminal voltage at around 12 v. $\pm \Delta v$, depending upon the state of transistor 1224. For example, with transistor 1224 in its normally off condition, the level of the signal applied to the base terminal of transistor 1234 is above +12 v. and reverse biases the transistor 1234 which is part of a differential amplifier circuit. With the transistor 1234 turned off, the other transistor 1236 of the differential amplifier is forward biased on as a result of the voltage level at the emitter terminal, resulting from current flow through a current source resistor 1238 and the potential developed across the collector resistor 1240.

With the differential amplifier in this state, the junction FET transistors 1242 and 1244 are turned on by a signal applied to the gate terminals from the collector terminal voltage developed across collector resistor 1240. With the FET transistors 1242 and 1244 turned on, the ground level signal received at the input terminals 1208 and 1210 are conducted through the source and drain terminals of FET transistors 1242 and 1244 to the output terminals 1214 and 1216, respectively. Since transistor 1234 of the differential amplifier is turned off, the voltage drop across a collector resistor 1246 is low, resulting in a low voltage level signal which is applied to the gate terminals of the FET transistors 1248 and 1250, thereby turning them off. As a result, the input signals $\omega_1 t_f$ and ω_{etf} applied to the input terminals 1204 and 1206 cannot be conducted to the output terminals 1214 and 1216, respectively.

When the switch signal R/LL applied to input terminal 1212 goes high, the interface resistor circuit 1218 is back biased, thereby raising the level of the signal at the lower end terminal of base current resistor 1220. This signal level is fed through the threshold circuit 1222 to forward bias the transistor 1224 to an on condition. When transistor 1224 goes on, current flow through the bias network, including resistors 1228, 1230 and 1232, causes the signal to the base terminal of transistor 1234 to go lower than +12 v., thereby turning on transistor 1234.

With the transistor 1234 of the differential amplifier turned on, the other transistor 1236 is turned off. Consequently, the voltage drop across collector resistor 1246 increases, and the voltage drop across collector resistor 1240 decreases. As a result, the collector voltage of transistor 1234 is fed to the gate terminal of FET transistors 1248 and 1250 to turn them on, whereupon the input signal $\omega_1 t_f$ and ω_{etf} are conducted through the source and drain terminals of the FET transistors to the output terminals 1214 and 1216, respectively. The

decrease in the voltage at the collector terminals of transistor 1236 is applied to the gate terminals of the FET transistors 1242 and 1244 to turn them off, whereupon the ground level signal applied to the input terminals 1208 and 1210 cannot be conducted to the output terminal.

The output signal β of the operational amplifier 1162 (FIG. 1B) then becomes $\beta = \eta_d + \eta_w + \eta_k$. If, however, it is a two gyro system, switch contacts of single gyro switch 1178 are switched and then this kinematic lead angle signal $\omega_1 t_f$ is fed to an input of operational amplifier 1180 whereupon the signal β becomes $\eta_d + \eta_w$.

The superelevation signal ϵ is also fed directly to the input of an operational amplifier 1252 to produce an output signal α where:

15

$$A = \epsilon$$

These output signals β and α from the operational amplifiers 1162 and 1252 can be fed directly through analog switches 1254a and 1254b of the previously described type to an input of the operational amplifiers 1180 and 1257, respectively, when the cant resolver signal C is at the off level. If the cant signal C is on, it can be first fed through a cant resolver 1256 before being fed through the analog switches 1254a and 1254b to the inputs of the operational amplifiers 1180 and 1257, respectively, when the cant resolver is turned on. Although a cant resolver is specifically referred to, it should be understood that other types of resolvers could be used instead.

20

Assuming that the cant resolver 1256 is in operation, the output signals α and β from the operational amplifiers are fed to one winding thereof and are resolved into turret coordinates which take into account the incline angle of the turret relative to the horizontal and produces output signals which are resolved in accordance with this cant angle. One way to 30 perform this operation would be to have a first winding which is connected to a pendulum so that the first winding is moved relative to a stationary second winding, whereupon the inductive coupling between the legs of the windings will vary with the position of the movable winding. The output signal of the 35 cant resolver 1256 then becomes an uncorrected deflection signal D' and an uncorrected elevation signal E' where:

$$D' = -\beta \cos C + \alpha \sin C$$

and

$$E' = \alpha \cos C + \beta \sin C$$

45

These uncorrected deflection and elevation signals D' and E' are then fed through the analog switches 1254a and 1254b, respectively, to an input of the summing inputs of operational amplifiers 1180 and 1257, respectively, wherein they are further corrected. Another input of the operational amplifiers 50 1180 and 1257 receives jump signals D_j and E_j , respectively, which are produced by the variable attenuators 1258 and 1260, respectively, for each selected ammunition. Another input of the operational amplifiers 1180 and 1257 receives the 55 parallax coefficient $(1/R - 1/R_c)$ generated by the function generator 990 of FIG. 1A. Another input to the operational amplifiers is gun barrel droop in deflection D_d and elevation E_d . The input terminals of operational amplifier 1180 has a gain set resistor therein which multiplies the parallax coefficient by the deflection parallax constant D_{pd} determined for each tank. The operational amplifier 1257 has a gain set resistor associated with the input thereof which effectively multiplies the parallax coefficient by the elevation parallax constant D_{pe} determined for each tank. If the system is a two-gyro 60 system, the angular turret rate in elevation signal ω_e times time of flight signal ω_{etf} is fed to another input of the operational amplifier 1257 to compensate for the kinematic lead angle in elevation.

55

When the two-gyro system embodiment is being used (FIG. 70 1B), the angular gun-line rate in elevation signal ω_e is fed to a second follow and clamp circuit 1262 of the type previously described with reference to FIG. 7 which stores it as a DC signal ω_e . This DC signal ω_e is fed through a slave multiplier 1264 of the type previously described wherein it is multiplied 75 by the time of flight signal T to produce an output signal ω_{etf} .

which is the kinematic lead angle in elevation. This kinematic lead angle in elevation ω_{et} is fed through the analog switch 1176b and SG switch 1178 to an input of operational amplifier 1257 and the kinematic lead angle in deflection ω_{1tf} is fed through SG switch 1178 to an input of the operational amplifier 1180 in the deflection channel.

The outputs of the operational amplifiers 1108 and 1257 are fed through the analog switches 1278a and 1278b of the previously described type which will conduct the signals only when the COMPUTE signal is received by them.

Operational amplifiers 1280 and 1282 receive the output signals from the analog gates 1278z and 1278b, respectively, along with a bore sight correction signal Db in deflection and a bore sight correction signal Eb in elevation, respectively. These operational amplifiers 1278a and 1278b generate the deflection correction signal D and elevation correction signal E which are fed to a servoamplifier.

Furthermore, while the salient features have been described with respect to a particular embodiment, it should be readily apparent that other modifications can be made within the spirit and the scope of the invention and it is therefore not desired to limit the invention to the exact details shown and described.

What is claimed is:

1. A land vehicle fire control ballistic computer comprising: computer channel means including a plurality of circuits including first circuit means having an input coupled to receive a range signal for operating on the range signal in accordance with a transfer function related to ballistic equations which includes terms for selected standard conditions including standard ballistic conditions and standard environmental conditions for a selected one of a plurality of ammunition types and second and third circuit means in a first output channel and a second output channel respectively for operating on the operated on range signal in accordance with transfer functions related to ballistic equations which include terms for the standard conditions to produce a time-of-flight signal on the first output channel and a superelevation signal on the second output channel; and
2. The land vehicle fire control ballistic computer of claim 1 in which said plurality of circuit means includes a plurality of individual operational amplifiers including a first common operational amplifier for operating on the range signal in accordance with a normalizing standard condition transfer function said second circuit means includes a second and a third operational amplifier coupled in series circuit relationship to operate on the operated on range signal for producing a time-of-flight signal on the first output channel and said third circuit means includes other first and second operational amplifier means coupled in series circuit relationship with one another to operate on the operated on range signal for producing the superelevation signal in said second output channel; and
3. The land vehicle fire control ballistic computer of claim 2 further including additional circuit means for producing fire control deflection signals and elevation signals in response to the time-of-flight signal and the superelevation signal including means for operating on the superelevation signal by a transfer function corresponding to a selected ballistic drift constant for an ammunition type and means for selectively summing the resultant signal with an angular turret rate in azimuth signal times the time-of-flight signal, and a crosswind signal times a crosswind coefficient constant signal for a selected ammunition type having combined therewith a partial derivative factor corresponding to the effects of changes in standard condition air pressure and air temperature times the time-of-flight time to produce a corrected deflection signal.
4. The land vehicle fire control ballistic computer of claim 3 in which said additional circuit means operates on the time-of-flight signal by a transfer function for an angular turret rate in elevation and selectively combines the resulting signal with the superelevation signal to produce a corrected elevation signal.
5. The land vehicle fire control ballistic computer of claim 1 in which said plurality of circuit means further includes additional circuit means for producing fire control deflection and elevation signals in response to the time-of-flight signal and the superelevation signal including means for operating on the superelevation signal by a transfer function corresponding to selected ballistic drift constant for an ammunition type and means for selectively summing the resultant signal with an angular turret rate in azimuth signal times the time-of-flight signal, and a crosswind signal times a crosswind coefficient constant signal for a selected ammunition type having combined therewith a partial derivative factor corresponding to the effects of changes in standard condition air pressure and air temperature times the time-of-flight time to produce a corrected deflection signal.
6. The land vehicle fire control ballistic computer of claim 5 in which said additional circuit means multiples the the time-of-flight signal by an angular turret rate in elevation signal and selectively sums the signal with the superelevation signal to produce a corrected elevation signal.
7. The ballistic computer for producing fire control signals for the ballistics of projectile types wherein the improvement comprises: first means coupled to receive a range signal for multiplying the received range signal by a function comprising a normalizing function to produce a normalized range signal which is standardized relative to a single function common to the ballistics of a plurality of projectile types; a first output channel for producing a time-of-flight signal and a second output channel for producing a superelevation signal, each of said output channels including a second means and a third means, said second means coupled to receive the normalized range signal for multiplying the normalized range signal by the single function common to the ballistics of a plurality of projectile types for producing a function signal, and said third means coupled to receive the function signal from said second means for multiplying the function signal by a function comprising an unnormalizing function for producing the ballistic signals for the projectile type; and
8. The ballistic computer of claim 7 in which the partial derivative means selectively coupled to receive the signal produced by at least one of said first through third means for multiplying the signal by the ratio of change in a standard condition to the standard condition and to sum the ratio of change in standard condition and the produced signal to produce a partial derivative signal times the produced signal.

operably multiplying the output signal of selected operational amplifiers in accordance with the first order approximation partial derivative corresponding to changes in selected standard conditions for correcting the time-of-flight signal and the superelevation signal for changes in the selected standard conditions.

3. The land vehicle fire control ballistic computer of claim 2 further including additional circuit means for producing fire control deflection signals and elevation signals in response to the time-of-flight signal and the superelevation signal including means for operating on the superelevation signal by a transfer function corresponding to a selected ballistic drift constant for an ammunition type and means for selectively summing the resultant signal with an angular turret rate in azimuth signal times the time-of-flight signal, and a crosswind signal times a crosswind coefficient constant signal for a selected ammunition type having combined therewith a partial derivative factor corresponding to the effects of changes in standard condition air pressure and air temperature times the time-of-flight time to produce a corrected deflection signal.

4. The land vehicle fire control ballistic computer of claim 3 in which said additional circuit means operates on the time-of-flight signal by a transfer function for an angular turret rate in elevation and selectively combines the resulting signal with the superelevation signal to produce a corrected elevation signal.

5. The land vehicle fire control ballistic computer of claim 1 in which said plurality of circuit means further includes additional circuit means for producing fire control deflection and elevation signals in response to the time-of-flight signal and the superelevation signal including means for operating on the superelevation signal by a transfer function corresponding to selected ballistic drift constant for an ammunition type and means for selectively summing the resultant signal with an angular turret rate in azimuth signal times the time-of-flight signal, and a crosswind signal times a crosswind coefficient constant signal for a selected ammunition type having combined therewith a partial derivative factor corresponding to the effects of changes in standard condition air pressure and air temperature times the time-of-flight time to produce a corrected deflection signal.

6. The land vehicle fire control ballistic computer of claim 5 in which said additional circuit means multiples the the time-of-flight signal by an angular turret rate in elevation signal and selectively sums the signal with the superelevation signal to produce a corrected elevation signal.

7. The ballistic computer for producing fire control signals for the ballistics of projectile types wherein the improvement comprises:

first means coupled to receive a range signal for multiplying the received range signal by a function comprising a normalizing function to produce a normalized range signal which is standardized relative to a single function common to the ballistics of a plurality of projectile types; a first output channel for producing a time-of-flight signal and a second output channel for producing a superelevation signal, each of said output channels including a second means and a third means, said second means coupled to receive the normalized range signal for multiplying the normalized range signal by the single function common to the ballistics of a plurality of projectile types for producing a function signal, and said third means coupled to receive the function signal from said second means for multiplying the function signal by a function comprising an unnormalizing function for producing the ballistic signals for the projectile type; and

partial derivative means selectively coupled to receive the signal produced by at least one of said first through third means for multiplying the signal by the ratio of change in a standard condition to the standard condition and to sum the ratio of change in standard condition and the produced signal to produce a partial derivative signal times the produced signal.

8. The ballistic computer of claim 7 wherein said partial derivative multiplier means includes a first partial derivative circuit means coupled in series circuit relationship between first means and said second means for summing the approximate partial derivative corresponding to changes in selected standard conditions relative to the standard conditions for correcting the normalized range signal in accordance with the effects thereon of the changes in selected standard conditions.

9. The ballistic computer of claim 8 wherein said first partial derivative circuit means combines a signal corresponding to the effects of changes in air pressure and air temperature on the normalized range signal.

10. The ballistic computer of claim 8 wherein said first partial derivative circuit means generates and combines with the normalized range signal, a signal

$$\left(\frac{\Delta T}{T_0} - \frac{\Delta P}{P_0} \right)$$

where ΔT is the change in air temperature, T_0 is the standard condition air temperature, ΔP is the change in air pressure and P_0 is the standard condition air pressure.

11. The ballistic computer of claim 8 in which the last said circuit means multiplies the time-of-flight signal by an angular turret rate in elevation signal and selectively sums the signal with the superelevation signal to produce a corrected elevation signal.

12. The ballistic computer of claim 8 wherein said partial derivative multiplier means includes a second partial derivative circuit means and a third partial derivative circuit means coupled in series circuit relationship to receive the ballistic signal from said third means for summing the approximate partial derivative corresponding to changes in selected standard conditions relative to the standard conditions for correcting the ballistic signals in accordance with the effects thereon of the changes in selected standard conditions.

13. The ballistic computer of claim 12 wherein said second partial derivative circuit means sums a signal corresponding to the effects of changes in air pressure and air temperature on the ballistic signals and said third partial derivative circuit means sums a signal corresponding to the effects of changes in muzzle velocity as a result of changes in propellant grain temperature, and a function of effective full charge.

14. The ballistic computer of claim 13 wherein said second partial derivative circuit means sums a signal

$$\left(\frac{\Delta T}{T_0} - \frac{\Delta P}{P_0} \right)$$

where ΔT is the change in air temperature, T_0 is the standard condition air temperature, ΔP is the change in air pressure, and P_0 is a standard condition air pressure and said third partial derivative circuit means sums a signal proportional to

$$k \left(\frac{\Delta T_g}{T_g} K_g \right) - f(E.F.C. \cdot K_e)$$

where ΔT_g is the change in propellant grain temperature, T_g is standard condition propellant grain temperature, K_g is derived ballistic constant for an ammunition type, E.F.C. is the effective full charge, K_e is a derived ballistic constant for an ammunition type and k is a + or 1 having a magnitude greater than 1.

15. The ballistic computer of claim 12 in which said first means and said third means multiply the received signals by linear functions derived from the effects of ballistic conditions and environmental conditions including the projectile mass m , projectile diameter d , drag coefficient K_D , and atmospheric density p , and initial projectile velocity V_0 , and said second means multiplies the received normalized range signal by a nonlinear function.

16. The ballistic computer of claim 15 in which said first means multiplies the received normalized range signals by approximately the term $m/pd^2 K_D$ and one of said third means multiplies the received signals by approximately the term $mg/2pd^2 V_0 K_D$.

17. The ballistic computer of claim 15 in which said first means multiplies the received normalized range signals by approximately the term $m/pd^2 K_D$ and one of said third means multiplies the received signals by approximately the term $m/pd^2 V_0 K_D$.

18. The ballistic computer of claim 12 in which said first means and said third means are adjustable for multiplying the received signals by individual ones of a plurality of constant functions, each including individual terms derived from the effects of ballistic conditions and environmental conditions on individual ones of a plurality of projectile types.

19. The ballistic computer of claim 7 including means for producing fire control deflection and elevation signals in response to the time-of-flight signal and the superelevation

15 signal including means for multiplying the superelevation signal by a selected ballistic drift constant for an ammunition type and selectively summing the resultant signal with an angular turret rate in azimuth signal times the time-of-flight signal, a crosswind signal times a crosswind coefficient constant for a selected ammunition type having summed therewith a partial derivative corresponding to the effects of changes in standard condition air pressure and air temperature times the time-of-flight time to produce a corrected deflection signal.

20. The ballistic computer of claim 7 in which said first means and said third means multiply the received signals by linear functions derived from the effects of ballistic conditions and environmental conditions including the projectile mass m , projectile diameter d , drag coefficient K_D , and atmospheric density p , and initial projectile velocity V_0 and said second means multiplies the received normalized range signal by a nonlinear function.

21. The ballistic computer of claim 7 in which said first means and said third means are adjustable for multiplying the received signals by individual ones of a plurality of constant functions, each including individual terms derived from the effects of ballistic conditions and environmental conditions on individual ones of a plurality of projectile types.

22. The ballistic computer of claim 7 in which said first means multiplies the received signals by approximately the function $m/pd^2 K_D$,

45 one of said third means operates on the received signals by approximately the function $mg/2pd^2 V_0 K_D$; and the other of said third means operates on the received signals by approximately the function $m/pd^2 V_0 K_D$

where:

m = projectile mass

p = air density

d = projectile diameter

K_D = projectile drag coefficient

V_0 = projectile initial velocity

g = gravitational effects.

55 23. The computer of claim 22 in which one of said second means multiplies the received signal by a function approximating

$$\left(\frac{e^2(R/R_n) - 1}{2(R/R_n)} - 1 \right)$$

60 and the other of said second means multiplies the received signal by the function approximating $(e(R/R_n) - 1)$ where:

R = range

$1/R_n$ = normalizing function $\approx$

$$1/m/pd^2 K_D.$$

70 24. The ballistic computer of claim 7 wherein said partial derivative circuit includes:

circuit multiplier means coupled to directly receive the output signal from at least one of said first, second, or third means for multiplying the output signal in operable parallel circuit relationship with the output of at least one of

said first, second, or third means by a signal related to the ratio of change in at least one of the predetermined conditions relative to the predetermined condition to produce a product signal; and summing means coupled in series circuit relationship with said first, second, and third means for directly receiving the product signal and directly receiving the output signal for summing the product signal and the output signal to produce the corrected signal.

25. The ballistic computer of claim 24 in which said circuit multiplier means is a master-slave time-division multiplier, said master multiplier being operable to receive input signals corresponding to the ratio of change in a standard condition to the standard condition to feed the received signal to a slave multiplier and said slave multiplier multiplies the output signal from at least one of said first, second, and third means by the ratio of change in a standard condition to the standard condition signal.

26. The ballistic computer comprising:
first means coupled to receive a range signal R for normalizing the range signal in accordance with standard conditions to produce a normalized range signal R/R_n where $1/R_n$ is a normalizing signal; means for multiplying the normalized range signal R/R_n by an approximate in-line partial derivative $(1 - (\Delta R_n/R_n))$ where ΔR_n is the change in the range normalizing signal to compensate for the effects of changes in the standard conditions air pressure and air temperature on the range; first and second nonlinear function generator means coupled to receive the corrected normalized range signal from said multiplier means for respectively generating a first nonlinear function signal common to a plurality of ammunition types and related to time-of-flight and a

second nonlinear function signal common to a plurality of ammunition types and related to superelevation; first and second multiplier means coupled to said first and second nonlinear function generator means, respectively, for receiving and multiplying the nonlinear function signals by respective unnormalizing terms for standard conditions to produce a time-of-flight signal t_f and a superelevation signal ϵ ; third multiplier means and fourth multiplier means coupled in series circuit relationship to said first multiplier means and said second multiplier means to respectively multiply the time-of-flight signal and superelevation signal by approximate first order partial derivatives

$$15 \left(1 + \frac{\Delta R_n}{R_n}\right) \left(1 - \frac{\Delta V_o}{V_o}\right) \text{ and } \left(1 + \frac{\Delta R_n}{R_n}\right) \left(1 - 2 \frac{\Delta V_o}{V_o}\right) \text{ where } V_o$$

is the standard condition muzzle velocity to correct for changes in the standard conditions of air temperature, air pressure, propellant grain temperature, and effective full charge;

means for multiplying the superelevation signals by ballistic drift constant signal for an ammunition type and to multiply the time-of-flight signal by the product of a ballistic crosswind constant signal for a specific ammunition type and a crosswind signal, to generate signals related to ballistic drift and crosswind deflection, respectively; and means for feeding the superelevation signal to an elevation channel and to sum and feed the ballistic drift and crosswind deflection signals to a deflection channel and resolver means for converting the signals to fire control elevation and deflection coordinate signals.
